US00D767606S

(12) **United States Design Patent** (10) **Patent No.:** **US D767,606 S**
Lee et al. (45) **Date of Patent:** **** Sep. 27, 2016**

(54) **DISPLAY SCREEN OR PORTION THEREOF WITH GRAPHICAL USER INTERFACE**

(71) Applicant: **Samsung Electronics Co., Ltd.**, Suwon-Si, Gyeonggi-Do (KR)

(72) Inventors: **Min Sun Lee**, Seoul (KR); **Olivia Lee**, Seoul (KR); **Han Chul Jung**, Seongnam-si (KR)

(73) Assignee: **Samsung Electronics Co., Ltd.**, Gyeonggi-do (KR)

(**) Term: **14 Years**

(21) Appl. No.: **29/498,916**

(22) Filed: **Aug. 8, 2014**

(30) **Foreign Application Priority Data**

Feb. 11, 2014 (KR) 30-2014-0006871

(51) **LOC (10) Cl.** **14-04**

(52) **U.S. Cl.**

USPC **D14/486**

(58) **Field of Classification Search**

(57) **CLAIM**

The ornamental design for a display screen or portion thereof with graphical user interface, as shown and described.

DESCRIPTION

FIGURE is the front view for a display screen or portion thereof with graphical user interface showing our new design.

The dot-dash line showing of a display screen or portion thereof forms no part of the claimed design. The remaining broken lines, showing portions of the graphical user interface, form no part of the claimed design.

1 Claim, 1 Drawing Sheet
